UNITED STATES PATENT OFFICE.

EARL C. HANSON, OF LOS ANGELES, CALIFORNIA.

WIRELESS TRANSMISSION OF SIGNALS.

1,320,140.

Specification of Letters Patent.

Patented Oct. 28, 1919.

Application filed August 27, 1917. Serial No. 188,392.

To all whom it may concern:

Be it known that I, EARL C. HANSON, a citizen of the United States, residing at Los Angeles, in the county of Los Angeles 5 and State of California, have invented certain new and useful Improvements in Wireless Transmission of Signals, of which the following is a specification.

The object of my invention is to provide 10 apparatus by which signals may be transmitted through space without wires.

My invention utilizes exclusively audio frequencies and employs transformers having iron cores in the place of the air core 15 type transformers commonly used in radio service. By using iron core transformers I am able to greatly increase the efficiency of the transformation and at the same time I produce a system which is selective in that 20 it absolutely eliminates all radio frequency waves by means of these transformers.

In the annexed drawing, a sending and a receiving station are shown, these stations being duplicates of each other and being 25 shown with the apparatus in the proper position to respectively send and receive a message.

Each of the stations comprises an antenna 1 connected to a switch 2 by means 30 of which the antenna 1 may be connected to a sending wire 3 or a receiving wire 4. The sending wire 3 is connected to one terminal of the secondary 5 of a sending transformer 6, the other terminal of the secondary 35 being connected by a wire 7 with the ground. The primary 8 of the transformer 6 is connected at one terminal directly with the brush 9 of the audio frequency generator 10, the other terminal of 40 the secondary 8 being connected by means of a wire 11 with a rheostat 12. The moving arm 13 of the rheostat 12 is connected to a contact pin 14 of a key 15, the moving arm 16 of the key 15 being connected 45 through a wire 17 with the other brush 18 of the generator 10. The transformer 6 is provided with an iron core 19.

The receiving wire 4 is connected to the primary 21 of a receiving transformer 22 50 having an iron core 23, the other terminal of the primary 21 being connected by means of a wire 24 with the ground. The secondary 25 of the transformer 22 is connected on one terminal to the grid 26 of 55 a vacuum bulb repeater 27. The other terminal of the secondary 25 is connected to

a moving arm 28 of an adjustable transformer 29 having an iron core 30, a primary winding 31 and a secondary winding 32. The moving arm 28 serves to cut in more or less of the primary winding 31.

The vacuum bulb repeater 27 is provided with a filament 33 energized by a battery 34. This filament is connected by means of a wire 35 with one terminal of both the primary 31 and the secondary 32. The secondary 32 is provided with a movable arm 36 which is connected to one terminal of the telephone receiver 37, and by which more or less of the secondary 32 can be cut in or 70 out. The other terminal of the receiver 37 is connected through a receiver battery 38 with the plate 39 of the vacuum bulb repeater 27.

The method of operation of my invention 75 is as follows:

The generator 10 is so constructed that it generates an audio frequency electric current and this current is passed through the primary 8 whenever the key 15 is depressed, 80 the rheostat 12 serving to regulate the flow of current through the primary 8. Whenever the key is depressed and the primary 8 is so energized a high potential of audio frequency is generated in the secondary 5, the 85 efficiency of transformation between the primary 8 and the secondary 5 being very high due to the iron core 19. This high audio frequency potential is impressed between the antenna 1 and the ground causing 90 audio frequency electro-static charges between the antennæ and the ground. These charges set up an electro-static field which includes the antenna 1 at the receiving station in which the switch 2 is turned to connect the wire 4 with the antenna 1. These electro-static charges cause small currents to flow from the antenna 1 through the primary 21 to the ground. These small currents induce a potential in the primary 25, 100 and this potential is utilized in the vacuum bulb repeater 27 to control the current flowing through the telephone receiver 37.

By the use of the transformer 29 there is formed what is known as a regenerator circuit which greatly increases the efficiency of the apparatus.

I claim as my invention:

An audio frequency wireless receiving station comprising an antenna; a receiving 110 transformer having a primary and a secondary winding and an iron core transformer

so arranged as to eliminate radio frequency waves; means for connecting said primary winding between said antenna and the ground; a vacuum bulb repeater having a filament, a grid, and a plate; an adjustable transformer having adjustable primary and secondary windings; means for energizing said filament; a telephone receiver connected through a receiver battery to said plate and through said adjustable secondary with said filament; means for connecting

one terminal of the secondary of the receiving transformer with said grid; and means for connecting the other terminal of said secondary through the primary of said adjustable transformer with said filament. 15

In testimony whereof, I have hereunto set my hand this 21 day of August, 1917.

EARL C. HANSON.
